ANTENNA SYSTEM

Trevor H. Clark, New York, N. Y., assignor to
 Federal Telephone and Radio Corporation,
 Newark, N. J., a corporation of Delaware

Application March 5, 1943, Serial No. 478,081

16 Claims. (Cl. 250—33)

1

This invention relates to improvements in antenna systems, and more particularly to a short wave crossed loop wave collector adapted for use for installation on board ships, especially on top of masts.

An object of this invention is to provide a novel improved antenna assembly including crossed loops, sense antenna and counterpoise, which is especially adapted for use in connection with direction finding systems aboard ships.

Another object of this invention is to provide an antenna assembly of the type described which can readily be mounted upon the usual ship mast structures.

A further object of this invention is the provision of an antenna assembly including crossed loops, sense antenna and counterpoise, in which the stray capacity between the crossed loops and the counterpoise is reduced to a minimum.

An additional object of this invention is directed to providing an antenna assembly including crossed loops, sense antenna and counterpoise in which the sense antenna and counterpoise are interconnected by a shielded dummy loop network immediately adjacent thereto.

Still another object of this invention is directed to a novel sense antenna-counterpoise circuit which assures 180° phase displacement between them and maximum coupling to a dummy loop network.

A still further object of this invention is the provision of an antenna assembly for direction finding systems on board ship in which the capacity effect of the mast upon which the antenna system is mounted is appreciably reduced.

An additional object of this invention is directed to a novel antenna assembly for direction finding purposes including a crossed loop, sense antenna and counterpoise, in which the counterpoise is positioned above the loop directly between it and the sense antenna.

With these and incidental suggestions in view, the invention consists in certain features of construction and combination of parts which are set forth in the appended claims, and a preferred form of embodiment whereof is hereinafter described with reference to the drawings which accompany and form part of the specification, wherein:

Fig. 1 is a vertical view, partly in section, of the general antenna assembly in accordance with the present invention;

Fig. 2 is a top plan view of the general antenna assembly illustrated in Fig. 1;

Fig. 3 is an enlarged cross-sectional view of the upper portion of the antenna assembly;

Fig. 4 is an enlarged cross-sectional view of one of the sense antenna rods forming part of the antenna assembly;

2

Fig. 5 is a top view of the dummy loop shield included in Fig. 3.

The general antenna assembly according to my invention will be readily apparent from a study of Figs. 1 and 2. Primarily it includes a generally vertical supporting rod 10 from the mid-point of which extend four radial arms 12 spaced 90° relatively to one another and attached to the rod 10 by means of a suitable connector 13. The bottom of the supporting rod 10 is held in a strengthening support 14 which, in turn, is mounted upon a generally hemispherical base member 16. The latter, in turn, may be attached to the top of a ship mast indicated at 17. The four arms 12 may be interconnected by bracing bars 20 attached thereto by suitable clamping devices 22.

The crossed loop in accordance with the present invention, is formed by two flexible shielded cables 24 and 26, the apices of which pass through a top mount 18, attached to the top of the supporting rod 10, the ends of which are fastened within the base member 16, and the central portions of which are held by fastening devices 28 on the ends of the respective arms 12. Above the top mount 18 is fixed an insulating ring 29 which supports a metal cap 30 from which projects a plurality of counterpoise rods 32. These rods are positioned at 90° relatively to one another and, according to one feature of the present invention they extend in a direction to bisect the angle between the crossed loops or, in other words, each counterpoise rod is at an angle at 45° to the loops immediately beneath and to either side of it. A sense antenna 34 extends vertically upwardly from an insulating disk 36 mounted on top of the cap 30.

By reason of the general arrangement just described it has been found that the capacity between the counterpoise and the crossed loop antenna is materially reduced by having the counterpoise rods extending at an angle bisecting the angle between the loops. By placing the counterpoise above the crossed loops, the capacity between the counterpoise and the mast is also reduced while, additionally, the juxtaposition of the sense antenna and counterpoise by reason of the described arrangement permits them to be directly interconnected, as by a dummy loop network without the interposition of a long transmission line.

The upper portion of the antenna system, and more particularly the top mount 18 and the cap 30 together with associated parts is more fully illustrated in Fig. 3. It will be seen that the top of the supporting rod 10 is provided with a flange 38, while the lower portion of the top mount 18 is provided with a comparable flange 40, which permits an easy assembly of the top mount upon the rod as by bolts 42. The insulat-

ing ring 29 is likewise attached to the top of the top mount 18 by means such as bolts 44 while the cap 30 is mounted upon the ring 29 by similar means such as bolts 46. The insulating disk 36 may be attached to cover the cap 30 by screws 48.

As previously described, the cap 30 serves to support the counterpoise rods 32 and, at the same time electrically connects one with the other. For this purpose the inner ends of the counterpoise rods are formed with stiffener sections 50 which may be provided with threaded extensions 52 projecting through openings in the cap 30 and secured thereto by nuts 54. The bottom of the sense antenna 34 is similarly provided with a stiffening section 56 having a threaded projection 58 extending through a central opening in the insulating disk 36 and attached thereto by nut 60.

The tops of the cables forming the two loops pass, as previously described, through the top mount 18. In order to securely hold the loops in place and prevent a strain upon the top, curved portions, the loops are securely held in openings in this top mount. For this purpose the openings in the top mount 18 may be provided with a Bakelite or other insulating bushing 62 through which is passed a metal sleeve 66 which, in turn, encloses a rubber sleeve 64 immediately surrounding and adapted to be pressed against the cable 24. The sleeve 66 is formed with a collar 68 on one end which presses against the inner end of the bushing 62, limiting movement of the sleeve 66 in the downward direction, and is threaded on its outer end. A cap 76 screws over the threaded end of the sleeve 66 and, through a metal washer 74, presses tightly against the rubber sleeve 64, squeezing it down the surface of the cable. In accordance with the present invention each loop is preferably formed from a flexible shielded cable, the shield being formed by an outer steel braid 78, plus an inner copper braid. This shielding braid is cut off just above the collar 68 and a ferrule 72, soldered to the braid, this ferrule projecting over the end of the collar 68 and assisting in preventing downward strain upon the cable. As is common practice in shielded loop construction the upper portion of each loop will be unshielded so that by removal of the braid 78, and any inner braid, if used, the top of each loop will consist solely of insulated conductor 78. In Fig. 3 there may also be seen the end of the cable 26 which may pass over (or beneath) the unshielded portion 78 of the cable 24. The cross-section of the unshielded cable 26 is indicated at 78'. In order to properly attach the cable holding means in the top mount 18, and to generally make connections within this top mount, the latter may be in a somewhat skeletonized form being provided with a plurality of through working apertures 77.

As previously mentioned, one of the advantages of the present construction lies in providing a short interconnection through a dummy loop between the sense antenna and counterpoise. Fig. 3 also shows the manner in which such a dummy loop assembly may be mounted with the top mount 18. This dummy loop network is preferably mounted within a shielding can 80, the network itself which may be of conventional form being diagrammatically indicated at 82. The can 80 is attached to a flanged cylindrical member 84 with a water-proof gasket 86 therebetween, as by means of screws 88. The cylindrical member 84 is internally threaded at its other end to receive a compression nut 90 which

squeezes a compression gland 96 between washers 94 and 98. Above the washer 96 is positioned a split sleeve 100 which supports a jack plug 102 against the gasket 86. A second gasket 104 spaces the jack plug 102 from the gasket 86. The jack plug 102, in turn, has connected thereto as by threaded extensions 106, the banana plugs 108 which extend upwardly into the can 80 for connection with the dummy loop network 82.

10 The two lines from the dual cable 92 are respectively attached to the lower ends of the banana plugs, the cable 92 thus acting as a transmission line from the dummy loop network down through the center of the hollow supporting rod 10 to the base member 16.

15 The lead-ins to the dummy loop through the shielding can 80 are brought to insulators 110 and 112, these lead-ins being respectively indicated at 114 and 116. The lead-in 114 may be interconnected with the sense antenna through the lead wire 118 connected to a tab 120 positioned beneath the nut 60. The lead-in to the counterpoise may be effected by the lead wire 122 connected to a tab 124 beneath the nut 54. Since the cap 30 to which all of the counterpoise rods are attached is conductive metal, the one lead wire 122 is sufficient for this purpose. As illustrated in Fig. 3 and with more particularity in Fig. 5 the dummy loop shield can 80 may also support part of a lightning arrester gap. On top of the shield can 80 is mounted, as by welding, a plate 136 from which projects upwardly a pointed rod 126 which, in turn, is spaced from a downwardly extending rod 128 which may also be attached to an extension on the tab 120. Since the shield can 80 is grounded to the mast through the screws 88, this arrangement serves inherently as a lightning arrester gap for the sense antenna 34.

20 One feature of the present invention lies in proper proportioning of the primary circuit of the dummy loop network 82. This circuit is so balanced that the resonant frequency as determined by the capacity of sense antenna to the counterpoise, the shielded loop and the mast, the capacity of the counterpoise to the shielded loop and the mast, the internal capacity of the primary winding of the transformer 200, the capacity of this winding relatively to the Faraday shield 202 and the inductance of the primary winding, will be greater than the operating frequency of the loop. By means of this proportioning, a phase displacement of exactly 180° between the sense antenna and the counterpoise can be obtained, and greater coupling to the dummy loop network results despite a decrease in the number of windings on the transformer. Adjustment of this primary circuit may be effected, if necessary, for optimum results by adjusting the length of the sense antenna or by providing a suitable capacitor (not shown) between the primary circuit and the Faraday shield.

25 For the purpose of properly proportioning the sense antenna to the counterpoise in their resonant circuit, such sense antenna may be formed as of an adjustable length in the manner more clearly indicated in Fig. 4. As there illustrated the counterpoise rod 34 itself is formed as a hollow tube slidable within a rod support 130. The latter may be shrunk at one end within a longitudinal bore of the rod stiffener 56, while its outer end may be split and externally threaded to receive a surrounding nut 132. When the nut 132 is tightened it will squeeze the rod support about the rod 32, thus, holding the same in place. When

the nut 132 is loosened, the rod 32 may be longitudinally adjusted as desired. The hollow rod 32 will be provided with a plug 134 in its end, which may be pressed into the end of the rod.

While it has not been specifically illustrated in detail, the counterpoise rods 32 may be formed adjustably in a manner identical with that just described in connection with the sense antenna rod 34. It is pointed out, furthermore, that adjustable rods such as have just been described are not required for a proper functioning of our antenna system since the proper length of rod can be previously calculated. However at times it may be desirable to make adjustments and for that reason such an adjustable type of rod may be preferred.

It will be clear to those skilled in this art that I have disclosed an antenna system which fulfills the objects primarily stated. While, in order to comply with the statutes I have described the various elements forming this antenna system in some detail, it will be obvious to those skilled in this art that various changes in details of construction may be effected without departing from the spirit of my invention. Accordingly, while I have described the principles of my invention in connection with certain specific apparatus, it is to be clearly understood that this description is made only by way of example and not as a limitation on the scope of my invention as set forth in the objects and the accompanying claims.

I claim:

1. An antenna system comprising, in combination, a shielded loop antenna comprising a pair of loops having a common axis and positioned at 90° relatively to one another, means for shielding said loop antenna, a vertical sense antenna extending upwardly above said loop antenna along the axis thereof, a counterpoise consisting of four radially directed rods mounted at 90° relatively to one another, and means for mounting said counterpoise coaxially with and above said loops, and below said sense antenna.

2. The combination according to claim 1, in combination with a dummy loop network, and circuit means interconnecting said sense antenna with said counterpoise, said circuit means including a transformer whose primary winding has such a number of turns it forms together with said sense antenna and counterpoise a resonant circuit whose resonant frequency is higher than that of said shielded loop.

3. The combination according to claim 1, in which the rods forming the counterpoise bisect the angles between the loops.

4. A wave collector including, in combination a hollow base member, a hollow supporting rod positioned on and communicating with said hollow base member, a hollow top mount, open at opposite vertical ends, supported on and communicating with the top of said supporting rod, four arms positioned at right angles to one another, extending radially outwardly from substantially the vertical mid-point of said supporting rod, a loop antenna comprising two loops, each loop having its top fixed to said top mount and its ends fixed in said base member, one loop being supported by two opposite arms and the other loop being supported by the other two opposite arms, whereby the two loops are positioned at 90° relatively to one another, means for shielding each loop, a cap mounted on said top mount, a vertical sense antenna supported from said cap, a counterpoise attached to said cap, said counterpoise comprising four radially

directed rods extending from said cap at right angles to one another, and transmission line means leading from said sense antenna and counterpoise through said hollow supporting rod to said base member.

5. The combination according to claim 4, in which each of said loops and the shielding means therefor is formed of shielded insulated flexible cable, in combination with means for insulating said shielded cable from said top mount.

6. The combination according to claim 4, in which each of said loops and the shielding means therefor is formed of shielded insulated flexible cable, and the shielding is removed from that portion of the loop within said top mount, in combination with means for insulating said shielded cable from said top mount.

7. The combination according to claim 4, in combination with means for insulating said cap from said top mount, and means for insulating said sense antenna from said cap.

8. The combination according to claim 4, in which said transmission line includes a dummy loop transformer network interconnecting said sense antenna and counterpoise and a dual cable leading from said network to said base, in combination with a hollow container enclosing said network, means for mounting said container inside of said top mount, and means for mechanically supporting said dual cable from said container.

9. The combination according to claim 4, in which the rods forming the counterpoise bisect the angles between the loops.

10. A wave collector including in combination a hollow base member, a hollow supporting rod positioned on and communicating with said hollow base member, a hollow top mount open at opposite vertical ends, supported on and communicating with the top of said supporting rod, four arms positioned at right angles to one another, extending radially outwardly from substantially the vertical mid-point of said supporting rod, a loop antenna comprising two loops, each loop having its top passing through said top mount and its ends fixed in said base member, one loop being supported by two opposite arms and the other loop being supported by the other two opposite arms, whereby the two loops are positioned at 90° relatively to one another, means for shielding each loop, an insulating ring fastened on said top mount, a metal cap attached to said insulating ring, an insulating disk covering said metal cap, a vertical sense antenna provided with a through bolt extending through said insulating disk, a counterpoise attached to said metal cap, said counterpoise comprising four radially directed rods extending from said cap at right angles to one another, a hollow metal container mounted within said top mount and grounded to said supporting rod, a dummy loop transformer network positioned within said container, means for interconnecting said dummy loop transformer network with said sense antenna and counterpoise, a dual cable leading from said dummy loop transformer network to said hollow base, a downwardly extending rod electrically connected with said sense antenna, and an upwardly extending rod attached to said metal container, the upper end of said rod being spaced below said downwardly extending rod to form with the latter a lightning arrester gap.

11. The combination according to claim 10, in which the rods forming the counterpoise bisect the angles between the loops.

75

12. The combination according to claim 10, in which each of said loops and the shielding means therefor is formed of a shielded, insulated flexible cable, in combination with means for insulating said shielded cable from said top mount.

13. The combination according to claim 10, in which each of said loops and the shielding means therefor is formed of a shielded, insulated flexible cable, and in which the shielding is removed from that portion of the cable within said top mount, in combination with means for insulating said shielded cable from said top mount.

14. The combination according to claim 4, in combination with a dummy loop network, and circuit means interconnecting said sense antenna with said counterpoise, said circuit means including a transformer whose primary winding has such a number of turns it forms together with said sense antenna and counterpoise a resonant circuit whose resonant frequency is higher than that of said shielded loop.

15. An antenna system comprising in combination a loop antenna comprising a pair of loops

5 having a common axis and positioned substantially at right angles to one another, means for shielding said loop antenna, a vertical sense antenna extending upwardly above said loop antenna along the axis thereof, a counterpoise comprising conductive means substantially symmetrically disposed with respect to said sense antenna and means for mounting said counterpoise coaxially with and above said loops and below said sense antenna.

16. An antenna system comprising, in combination a loop antenna comprising a pair of loops having a common axis and positioned substantially at 90° relatively to one another, means for shielding said loop antenna, a vertical sense antenna extending upwardly above said loop antenna along the axis thereof, a counterpoise consisting essentially of a plurality of radially directed rods mounted substantially symmetrically with respect to said loops, and means for mounting said counterpoise coaxially with and above said loops and below said sense antenna.

TREVOR H. CLARK.
